UNITED STATES PATENT OFFICE.

SILAS B. HOVEY, OF KANSAS CITY, KANSAS.

CURTAIN-SUPPORTER.

1,106,566.

Specification of Letters Patent. Patented Aug. 11, 1914.

Application filed February 15, 1913. Serial No. 748,766.

To all whom it may concern:

Be it known that I, SILAS B. HOVEY, a citizen of the United States, residing at Kansas City, in the county of Wyandotte 5 and State of Kansas, have invented certain new and useful Improvements in Curtain-Supporters, of which the following is a specification.

This invention relates to new and useful 10 improvements in curtain supporters.

The object of this invention is the provision of a curtain supporter which is so constructed that it will retain both the curtain and shade in their proper positions against 15 any undesired displacement.

Another object of this invention is the provision of a shade supporter which can be adjusted to suit a window frame of any desired size.

20 A further object of this invention is the provision of a device of the nature described which will be comparatively simple and inexpensive to manufacture, reliable and efficient in use and readily operated.

25 With the above and other objects in view, this invention resides in the novel features of construction, formations, combinations and arrangements of parts to be hereinafter more fully described, claimed and illustrated 30 in the accompanying drawings, in which:

Figure 1 is a front elevation of my invention. Fig. 2 is a top plan view thereof. Fig. 3 is an end elevation. Fig. 4 is a longitudinal sectional view thereof. Fig. 5 is a transverse sectional view taken on the line 5—5 35 of Fig. 1, and Fig. 6 is a similar view taken on the line 6—6 of Fig. 1.

40 Referring to the accompanying drawings by similar characters of reference throughout the several views, the numeral 10 designates generally a portion of a window frame comprising the usual horizontal rail 11 connected by the customary vertical rails 12 between which are slidable the customary 45 sashes 13.

As clearly illustrated in Fig. 1 of the drawings, the window frame 10 extends inwardly beyond the line of the wall 14 to produce shoulders 15 for engagement with 50 a pair of supporting plates 16 and 17. These plates 16 and 17 are formed adjacent their rear edges with inwardly extending prongs 18 for engagement with the shoulders 15 of the rails 12 whereby these said plates will 55 be held against any undesired displacement.

A pair of telescoping rods 19 and 20 are

secured to the inner sides of the plates 16 and 17 respectively adjacent their rear edges so that the inner end of the rod 19 will be 60 slidably located within the inner end of the rod 20. The rod 19 is formed with a longitudinally extending bore 21 for engagement with a threaded adjusting rod 22 which extends through the said rod 20 and through an opening formed in the plate 17. The outer end of the rod 22 is equipped with an angular head 23 which engages a surrounding 65 washer 24 located upon the rod 22 and contacting with the adjacent face of the plate 17.

A locking nut 25 is threaded upon the rod 22 and is longitudinally movable within the rod 20 to contact with the adjacent end of the rod 21 for limiting the inward movement of the rod 19 as desired. Obviously 70 upon the rotation of the rod 22 the plates will be drawn inwardly causing the prongs 18 to engage the shoulders 15 thereby holding the said plates 16 and 17 against any 75 undesired displacement. The plates 16 and 80 17 are formed with outwardly extending extensions or plates 26 off-set at their free ends as at 27 to produce ears for engagement with telescoping rods 28 and 29 which further insures the said plates 16 and 17 against any 85 undesired displacement.

Brackets 30 are 85 slidable on the rods 28 and 29 and are held in their adjusted positions against sliding movement by set screws 31. The inner sides of these brackets 30 have secured thereto 90 rearwardly and inwardly curved arms 32 terminally equipped with bearings 33 for 95 slidable engagement with the rods 19 and 20. The lower terminals of the brackets 30 are provided with sockets 34 for receiving the 95 opposite ends of a curtain roller indicated by the dotted lines and designated by the numeral 35. The upper ends of the brackets 30 are formed with openings for the reception of telescoping rods 36 and 37, which not only constitute a brace for the said brackets 100 but also a convenient curtain support.

From the foregoing it will be seen that the plates 16 and 17 may be attached to a window frame of any size, and also that the 105 brackets 30 are so mounted that they will not only engage a curtain pole and shade roller of any length but may be so positioned that the shade or curtain can be moved to cover either the entire or any portion of the 110 sashes 13.

From the foregoing disclosures taken in

connection with the accompanying drawings it will be manifest that a curtain supporter is provided which will fulfil all of the necessary requirements of such a device.

Having thus fully described this invention what I claim as new and desire to protect by Letters Patent is:—

1. In a device of the class described, the combination with a pair of end plates, of two adjustable rods extending between said end plates one of said rods being disposed in front of the other, a pair of brackets connected with and bodily slideable on both of the two rods, each bracket having an upwardly extending arm and a downwardly extending arm, a hanger rod mounted in the upwardly extending arms and a roller member mounted in the downwardly extending arms.
2. In a device of the class described, the

combination with a pair of oppositely disposed end plates, of two telescoping rods connecting said end plates, one of said rods being disposed in front of the other, a pair of bracket members bodily slideable on the front telescoping rod and having rearward extensions slidingly engaging with the rear-most telescoping rod, said brackets having upwardly extending arms and downwardly extending arms, a telescoping rod mounted in the upwardly extending arms, and a roller mounted in the downwardly extending arms.

In testimony whereof I affix my signature, in the presence of two witnesses.

SILAS B. HOVEY.
